SAFETY RAZOR

Bernard E. Davis, Brooklyn, N. Y.

Application March 1, 1934, Serial No. 713,504
Renewed June 11, 1936

23 Claims. (CL. 30—40)

My present invention relates to razors, and more particularly to a novel and highly improved type of safety razor.

There have been many attempts made in the past to provide a safety razor of the magazine type. These prior devices have either proven cumbersome in usage or incapable of competition with refillable safety razors because of excessive manufacturing costs. Accordingly it may be stated that it is one of the main objects of the present invention to provide a safety razor of the magazine type which is compact, economical in usage and cost, and highly efficient in shaving.

Another important object of the invention is to provide a safety razor which generally comprises a casing having a plurality of spaced blades carried by spaced endless belts between a pair of spaced prismatic devices, the faces of one of the devices functioning as blade carrier faces.

Another object of the invention is to provide a safety razor including a revolvable blade carrier device, the device being provided with means for automatically moving the razor blade clamp out of clamping position when the device is adjusted to change a blade.

The novel features which I believe to be characteristic of my invention are set forth in particularity in the appended claims. The invention itself, however, both as to its organization and method of operation, will best be understood by reference to the following description, taken in connection with the drawings, in which I have indicated diagrammatically several constructions whereby my invention may be carried into effect.

In the drawings:—

Fig. 1 shows a sectional view of the razor, looking in the direction of the arrows, taken along line 1—1 of Fig. 2.

Fig. 2 is a side view of the razor with one of the side walls removed,

Fig. 3 is a sectional view taken along line 3—3 in Fig. 2 and looking in the direction of the arrows,

Fig. 4 is a sectional view along line 4—4 in Fig. 2 looking in the direction of the arrows,

Fig. 5 is an end view of the razor as shown in Fig. 2, showing the head of the device arranged for operation,

Fig. 6 is a side view of the support frame,

Fig. 7 is a plan view of the detail shown in Fig. 6,

Fig. 8 is a detail view of one of the combined blade support and belt driver devices,

Fig. 9 is an end view of the detail shown in Fig. 8,

Fig. 10 shows a modified form of blade and carrier,

Fig. 11 shows a further modified form of blade and carrier,

Fig. 12 is a sectional view of another form of blade and carrier construction,

Fig. 13 is a view similar to Fig. 9, adapted for use with a carrier of the type shown in Fig. 12,

Fig. 14 is a partial side view of the operating head of a modified form of the invention,

Fig. 15 is a front view of still another modification of the invention,

Fig. 16 is a view taken along line 16—16 in Fig. 15 looking in the direction of the arrows.

Referring now to the accompanying drawings, 15 wherein like reference characters in the different views designate similar structural elements, there is shown in Fig. 2 an assembly view of a safety razor which essentially comprises a casing 1, a blade conveyor 2, a pair of multi-function prisms 5, 5', a plurality of blades 6, a blade clamp 7 and a spacer frame 8. The embodiment shown in Fig. 2 has its casing 1 constructed of relatively thin suitable material. Such material may be sheet metal, phenol condensation products, hard 25 rubber and the like. However, the ends of the side walls, acting as bearings for prisms 5, 5' are to be springy or resilient. The casing, as shown in Fig. 3, has a rectangular cross section, the rear wall 1' being secured to the main body 30 in any desired manner. It is to be understood that the casing walls may be integral with each other or separable.

The operating end of the casing, or head thereof, is provided with clamp 7. The latter is pivotally secured to the side walls of casing 1 by securing it at the ends 9 of its top edge to the side walls of the casing adjacent the bottom face of the front edge of the top wall of the casing. Fig. 5 shows, in enlarged view, the relation between the clamp 7 and the open front end of casing 1. In order to positively maintain the clamp 7 in blade retaining position, the clamp is provided with a pair of securing arms 10, 10', the latter being integral with the clamp and extending 40 from the edges thereof towards the side walls of the casing. The free ends of the extending clamp arms 10, 10' are spring pressed against the casing walls by virtue of the construction of the two arms. That is to say, the arms are of thin material and biased towards the casing walls.

By providing the free ends of the clamp arms with teats 11, 11', and the ends of the casing side walls with cooperating depressions 12, 12', snap fastener securing means are provided be-

tween the clamp arms and the ends of the casing side walls. Since the ends of the casing side walls are constructed to be resilient and biased towards each other, it will be seen that when the free ends of arms 10, 10' are snapped into position against the ends of the casing walls, the clamp 7 will be firmly retained in the position shown in Fig. 2. In Fig. 5 and Fig. 2 are shown the dimensional relations between the area of clamp plate 7, the inclined open end of casing 1 and the blade positioned under the clamp. It will be observed that the plane of the open end of casing 1 is inclined at an angle of approximately 60 degrees with respect to the plane of the top wall, thus providing a correct shaving angle.

The blades 6 are actuated into cutting and storage positions by the prisms 5, 5'. Since the prisms are substantially similar in construction, only the prism 5 will be described in detail. It is to be clearly understood, however, that the member 5' is included in this detailed description. Figs. 8 and 9 show the construction of prism 5 in detail. It essentially comprises a body having a triangular cross section. Each vertex 13 is provided with a plurality of spaced teeth 14; three blade support faces 15 are thereby provided on each prism. Each support face 15 is actually a blade guard, because it is provided with a row of teeth 14 adjacent to, and slightly under, the cutting edge 6' of the blade 6 positioned on the support face.

In order to position the prisms 5 and 5' adjacent either end of casing 1, each prism is provided with a pair of opposed collars 16 axially aligned. The collars 16 provided on the prism 5 are disposed in bearings 17 provided in the front end of the side walls of the casing 1, while the collars 16' of the rear prism 5' are disposed within the bearings 18 provided in the rear end of the side walls of the casing adjacent the rear wall 1'. The bearings 17 and 18 are circular openings which may be provided in the side walls of the casing 1. Each prism is further provided with a pair of axially aligned sprocket members 19, and it will be noted that each of these sprocket members has a substantially triangular configuration, as shown in Fig. 9. The purpose of this configuration is to keep each blade sufficiently away from the center of its prism, and yet sufficiently close to the vertices of the prism to allow proper clearance between the blade and the vertices and thus enable the blade to rest firmly on a support face 15.

At the vertices of each of the sprocket members 19 there are provided pins 20. These pins are spaced substantially 120 degrees apart, and they function to convert the rotary motion of the prisms into linear movement of the blade carrier elements. Between each sprocket member 19 and the main body of each prism there is provided a circular groove 21, and the function of these grooves 21 is to serve as a means for permitting the spacer frame 8 to positively maintain the prisms in the position shown in Fig. 2. A knurled headed manipulating knob 22 may be rigidly secured to either of the prisms 5 or 5', and in Fig. 1 this knob 22 is shown secured to the rear prism 5'. However, and for convenience in manufacturing as well as assembly, this knob may be secured to either end of either of the prisms 5 and 5'. To permit such choice of position for the knob 22, there are provided in each of the prisms 5 and 5' a pair of threaded taps

23. It will be observed that each pair of taps in each prism is axially arranged.

The knob 22 is provided, of course, with a threaded shank, so that the knob 22 may be screwed into any of the taps provided in the prisms 5 and 5'. The remaining taps 23 may also be used for securing the side walls to the prisms 5, 5' by the use of flat head machine screws. From the details shown in Fig. 8 it will also be noted that the grooves 21 and the collars 16 are of substantially the same diameter.

In addition to the support provided for the prisms 5 and 5' by the bearings 17 and 18, there is provided auxiliary support by the spacer frame 8. The constructional details of the spacer frame are shown in Figs. 4, 6 and 7. From Fig. 6 it will be observed that the frame comprises a pair of spaced parallel members 30 and 31, the lower member 31 being longer than the upper one. The members 30 and 31 are made of springy sheet metal, and are integral with each other. In order to render the entire razor as light as possible, a substantial portion of each member 30 and 31 is stamped out and, as shown in Figs. 6 and 7, each of the members in actual construction is really a thin rectangular frame of springy metallic material joined together as at 31'. The ends of the members 30 and 31 have secured to them pieces of felt 32 and 33. These felt pieces are inclined towards each other and, as shown in Fig. 6, when viewed from the side as in Fig. 2, furnish with the members 30 and 31 a substantially trapezoidal configuration. Each piece of felt not only functions as a blade wiper in a manner to be described below, but essentially serves as a barrier against moisture penetrating to the inner blades. Each felt piece is provided with corner recesses to permit the ready passage of the blade carrier belts. Thus, the felt wiper 32 is provided in its upper corners with recesses 34, and with recesses 35 in its lower corners. It will be noted that the members 30 and 31 are bent into the shape shown in Fig. 6 from a single blank, the free ends being bent towards each other as shown.

Similarly the felt wiper 33 is provided with spaced upper corner recesses 36, and lower corner recesses 37. It will be noted from Figs. 2 and 4 that each inclined felt wiper extends between the upper and lower walls of the casing 1, and that the upper and lower edges of each felt wiper between the corner recesses are in substantial contact with the inner faces of the upper and lower walls of the casing 1 and that the ends of the felt pieces are in contact with the side walls of the casing 1.

On the outer face of each felt wiper there is provided a pair of spaced braces or brackets. The braces 38 provided on the outer face of the felt wiper 32 function to cooperate with the grooves 21 provided in prism 5 to positively retain this prism in its position. Each of the braces 38, and this detailed description applies with equal force to the braces 39 provided on the outer face of the felt wiper 33, is constructed of a flat sectional metallic band. The sectional band, in the case of each brace, is bent into a configuration as shown in Fig. 6, and it will be observed that each brace comprises a substantially arcuate portion 40 adapted to fit into its respective groove provided in one of the prisms 5 and 5'. Furthermore, each of the braces is provided with upper and lower rolled ends 41. The function of these rolled ends is to keep the belts as far apart, and as close to the upper and lower walls of the casing, as pos-

sible. In this way sufficient space is provided inside the casing to house a container of shaving cream or the like.

It will be observed that each of the braces 38 is provided with the rolled ends 41, and that each of the braces 39 is provided with similar rolled ends 41'. Upper and lower bolts 42 may be used to secure each brace to a felt wiper, as well as to the immediately adjacent portions of the members 38 and 31. Each pair of braces 38 and 39 may be shaped out of a single blank of sheet metal, and the rolled ends of the braces then be formed from the horizontal edges of the blank.

The blades 6 extend substantially between the side walls of casing 1, as shown in Fig. 1, and are secured at opposite ends to a pair of endless belts 50, 51. The belt 50 is provided with a plurality of spaced apertures 52 which register with the pins 20 provided on the sprocket members of prisms 5 and 5'. Similarly, a plurality of spaced apertures 53 are provided in the belt 51, and these apertures are used for a similar function. It will be noted from Fig. 1 that the end of each of the blades 6 is secured to its belt between a pair of successive apertures. Each end of a blade 6 may be secured to its belt by any well known means, as by riveting, and it is to be understood that the numeral 54 denotes the securing means, such as a rivet, for rigidly securing one end of a blade 6 to belt 51, whereas the numeral 55 denotes the securing means which retains the opposite end of the blade on the belt 50.

Each blade is provided with a single edge 6', and its cutting position is shown in Fig. 5 and Fig. 2. It will now be seen that when the knob 22 is actuated, as in a clockwise direction, the prism 5' is rotated in a similar direction, and the pins 20 mounted upon its sprocket members register with the apertures 52 and 53 to move the belts in a clockwise direction. This results in the replacement of one blade by the blade immediately below it on prism 5. Each of the belts 50 and 51 travels through the recesses 34, 35, 36 and 37 of the felt pieces 32 and 33. The dimensional relationship between the width of each belt 50 and 51, and the recesses in the felt wipers is clearly shown in Fig. 4, and it will be further noted that the inner edges of the members 30 and 31 extend somewhat beyond the recesses in the felt wipers.

Because of this construction, each blade is pulled through the felt wipers 32 and 33, as the belts move in a clockwise direction. In other words, and considering the blade 6 immediately preceding the felt wiper 32 in Fig. 2, assume that the knob 22 has just been rotated. This will result in the blade under consideration being pulled towards the upper edge of the felt wiper 32, and it will be seen that the said upper edge of the felt wiper will be pressed forward. A function of these felt wipers will, therefore, be seen to consist in absorbing the moisture from the blades as the blades are pulled over the edges of the wiper. Of course, the primary function of the felt spacers is to allow the blades to go through as close as possible to the casing walls, thereby to create space inside the casing, without marring the edges of the blades, as well as to keep moisture away from the inner blades.

The vertices 13 of the front prism 5, besides functioning as blade guards, additionally function as a cam member for pushing the blade clamp 7 a sufficient distance away from the elements associated with prism 5, so that a new blade may be readily substituted for an old blade without interference with the clamp 7. When vertex 13 of

prism 5 contacts with the inner face of clamp 7, and the prism 5 is still further rotated in a clockwise direction, the pressure against the inner face of clamp 7 will result in uncoupling of the arms 10, 10' from the side walls of casing 1. Of course, the free ends of arms 10 and 10' are of sufficient length to remain biased against the side walls of casing 1 even when the clamp 7 is pushed forwardly to its most extreme position. When the new blade has been moved into position, it is merely necessary to press down on the outer face of clamp 7 and push the arms 10 and 10' back to its original position. The free ends of these arms will snap into positive coupling with the side walls of casing 1, because of the snap coupling 11, 12 and 11', 12', due to the springy construction of the arms and the side walls of the casing.

Additional means is provided for positively maintaining the prisms 5 and 5' in desired position, such as for example shown in Fig. 2. The detailed construction of this additional means is shown in Figs. 8 and 9, and it will be noted that the outer face of each sprocket member 19 is provided with three spaced depressions 60. These depressions are in axial alignment with pins 26, 25 and therefore these depressions 60 are spaced at substantially 120 degrees apart. The inner faces of the ends of the side walls of casing 1 are provided with four groups of snap elements. Each group of snap elements comprises three members 30 registering with the three depressions 60 in the sprocket member face immediately adjacent the inner face of the casing wall. Thus, as shown in Fig. 3, adjacent the outer faces of the ends of prism 5 there is provided the snap member 35 61. Due to the spring construction of the ends of the side walls of casing 1, and the normal bias of these walls towards the ends of prism 5, as well as prism 5', the three protuberances 61 on the inner face of the side walls of casing 1 adjacent the depressions 60 will snap into their corresponding depressions, as for example when the prisms are in the position shown in Fig. 2.

Such snap protrusions may be provided on the side walls of the casing by punching, or any other operation. When the knob 22 is rotated, the snap couplings between the depressions 60 and the outer face of the sprocket members of prism 5' will be broken, and through the medium of the belts 50 and 51 similar uncoupling force 50 will be applied to the prism 5. It is to be understood, however, that there is sufficient resiliency imparted to the side walls of casing 1 to force the protrusions 61 into snap position when a blade 6 is in cutting position and the clamp 55 7 has been snapped into clamping location.

It will now be seen that the present safety razor construction enables the user to utilize a given blade 6 as long as he desires. As soon as a new blade is desired the knob 22 is rotated in 60 clockwise direction, and this results in one of the vertices 13 pushing the clamp 7 into its most extreme position, and a new blade is presented on a new blade support face of the prism 5. The clamp 7 is then snapped back into position, and 65 the blade may be used as long as desired. As many as thirty, more or less as desired, blades may be provided on the two belts, and these blades, because of the endless belt construction, can be used over and over again. It will be 70 realized at this point that one of the advantages of the present construction resides in the fact that there is always a blade 6 positioned for shaving. Thus, the person using the razor need never find himself without any blades to use. 75

When the blades are all dulled the entire razor construction is thrown away, and a new razor is purchased with a fresh magazine of blades within the casing all in one unit.

5 The economical construction of the present razor is such that it is cheaper to buy an entire new razor with its magazine of blades, than to purchase a new supply of blades alone for the existing type of safety razor. By splitting 10 the casing 1 centrally in two parts, along the sides, and hinging one side, the casing can be made permanent and a reload of blades inserted in position. This construction may be preferred for razors wherein the casing 1 is of 15 expensive material, such as gold, and it is only desired to replace an old group of blades by a new group. It is pointed out that it is a relatively simple matter to assemble the belts, prisms and frame for insertion within the casing 1, and 20 this is accomplished by clamping the members 30 and 31 towards each other and sliding the frame endwise between the prisms and the belts. Release of the clamping force results in the assembly shown in Fig. 2. The belts will not only 25 be tightly spaced, but the prisms 5 and 5' will be retained in their position as shown in Fig. 2. The assembled sub-unit is then inserted in proper position in the casing 1.

Various modifications may be made in the construction shown in Figs. 1 to 9 inclusive. For 30 example, air circulation apertures may be provided at various points in the casing 1, and preferably between the felt pieces and the casing ends. Again, the rear wall 1' of the casing may 35 be replaced by a construction similar to that shown at the cutting end of the razor, and in this way a double headed razor will be provided. In that case each blade can then be provided with a double edge. Also, a hood will be provided 40 for the operating head.

The blades and blade carriers may be modified in any desired manner, and several such modifications are shown in Figs. 10, 11 and 12. In Fig. 10, for example, the blades are shown as 45 having recesses cut in their corners whereby the carrier belts 70 and 71 have secured to them the extensions 72 and 73 of each blade 74. In this form of construction the belt is driven by means of the sprocket members described heretofore, 50 and the apertures provided in each belt.

In Fig. 11 is shown a modification of the construction shown in Fig. 10, wherein the blades are integral with the belts 70' and 71', the blade 74' being integral, as at 72', with the belts. In 55 this form of construction the belt and blade may be stamped out of the steel band sheeting used to manufacture blades. Of course, in any of these modifications the blade is preferably of rustless steel.

60 In Fig. 12 is shown, only in sectional form for simplicity of description, another modification wherein the blade 80 is riveted at its ends to the carrier belts 81 and 82, the inner faces of the belts being provided with spaced pins 83 and 84. These pins are provided in registration with the rivets securing the blades to the belts. The pins and rivets can be integral, if desired.

In Fig. 13 is shown how a prism would be modified to coat with a belt construction of the type 70 shown in Fig. 12. It will be noted that it is merely necessary to replace the pins 20 on each sprocket member 19 of the prisms by taps 75 registering with the pins 83 and 84 provided on the inner faces of the belts. Otherwise, the con-

struction of the prism is substantially the same as shown in Figs. 8 and 9.

The pivoted clamp 7 may be replaced by a clamp member 7' which is integral with, or fixedly attached to, the top wall of casing 1. Furthermore, the manual operating knob 22 may be affixed to the prism 5, and in Fig. 14 these modifications are illustrated. Because of the resilient construction of the clamp member 7', a vertex 13 of prism 5 will push the inwardly biased clamp 7' to the left, and retain the clamp in such displaced position as a new blade with its new support surface 15 is moved into shaving position, the continued upward movement of the vertex 13 then resulting in a gradual movement 15 of the clamp 7' to its clamping position. Since the remaining elements in this modification of the invention are the same as in Figs. 1 and 2, such elements are not included in Fig. 14.

Figs. 15 and 16 show still another modification 20 of the invention wherein only a single prism is employed. Three blades are shown used in this construction. Of course, the number of blades used depends on the number of support faces. Basically, however, the construction is the 25 same as that shown in connection with the prism 5 in Figs. 3, 5, 8 and 9. That is to say, the prism 90 corresponds to the prism 5 in Fig. 3 and the blades 91 are secured to the three faces 30 of the prism. Any desired means, such as rivets or locating pins, can be used to secure the blades.

The operating knob 92 is rigidly secured to the prism 90 by means of the snap construction 23 in Fig. 8. The sprocket members 19, and the collars 16, and the pins 20 are eliminated in this 35 form of the construction, but the depressions 60 and the protrusions 61 are retained. A clamp member 93 is pivoted to the top wall of the casing 94, and the two snap fastener arms 95 are employed as in the case of Fig. 5. The numeral 40 40 denotes the handle of this form of razor. The vertices 97 of the prism 90 are provided with the spaced teeth. This compact form of razor is used in the same manner as described heretofore. The knob 92 when moved in clockwise direction results in a vertex 97 pushing the clamp 93 away from clamping position, and a new blade is moved into shaving position. When this new 45 blade is in position the clamp 93 is pushed towards its normal clamping position, and the arms 95 snap back into their normal position.

50 While I have indicated and described several arrangements for carrying my invention into effect, it will be apparent to one skilled in the art that my invention is by no means limited to the particular constructions shown and described, but that many modifications may be made without departing from the scope of my invention, as set forth in the appended claims.

55 What I claim is:—

1. A safety razor comprising a casing provided 60 with an opening in at least one side thereof, a blade clamp arranged adjacent the opening, a blade carrying member revolvably mounted in said casing, a plurality of blades associated with the member, said member having a prismatic configuration and having its edges provided with a plurality of slots to form a plurality of combs, means for positively maintaining said member fixed with respect to said casing when a blade 65 is in cutting position, and additional means for moving said prismatic member through an arc whereby an edge thereof displaces said clamp into a position to permit a new blade to move 70 into the position of a used blade.

2. A safety razor comprising a casing with an opening in one side with a movable blade clamp arranged adjacent said opening, a multi-faced member revolvably mounted in said casing, a blade disposed on at least one face of said member, additional blades provided in said casing, said member being provided with a plurality of blade guard edges, each edge being adapted to move the clamp from its normal position when a blade under the clamp is to be replaced.
3. In a razor, as defined in claim 2, a second multi-faced member revolvably mounted in said casing, an endless belt driven by said two members, and all of said blades being secured to said belt.
4. In a razor, as defined in claim 2, means provided on said member and casing for positively locking said member in shaving position when a blade is positioned under the clamp.
5. In combination, in a safety razor, a casing provided with at least one opening, an adjustable member provided with at least two blade support faces and at least one row of blade guard teeth at the line of intersection of said faces, said member being revolvably mounted between the walls of said casing adjacent said opening, a second member disposed within the casing adjacent the end opposite to the said opening, a plurality of razor blades, a pair of belts coupling said two members whereby adjustment of one of the members imparts motion to the other through said belts, said blades being secured to the belts in spaced relation, one of the faces of said first member being positioned in shaving position when one of the blades is in contact therewith, a blade clamp secured to said casing, detachable means for positively maintaining the clamp in contact with said one blade, and means for revolving said first member to replace said one face and the blade thereon by a second face and a new blade.
6. In a safety razor combination, as defined in claim 5, the path of said guard teeth being such that adjustment of the adjustable member results in said clamp being detached from said casing, and a spacer frame disposed within said casing to maintain the belts spaced apart.
7. In a safety razor, as defined in claim 5, a frame disposed within said casing, said frame including spacer bands adapted to contact with the said belts and space them apart to an extent such that the blades carried from the belts are slightly spaced by the casing walls, and the space between said bands being adapted to receive a container.
8. In a razor, as defined in claim 5, a frame disposed within the casing, said frame including spacer means in contact with the inner faces of the belts, and auxiliary means in end thrust contact with the said two revolvable members.
9. In a razor as defined in claim 5, at least two moisture barrier sheets disposed within the casing, each sheet being positioned adjacent a revolvable member.
10. A safety razor comprising a casing provided with an opening in one side thereof, a blade clamp arranged adjacent said opening, a multi-faced blade carrier member disposed within the casing, a blade disposed on at least one face of said member, additional blades provided in said casing, and said member being provided with a plurality of blade guard edges.
11. In a razor as defined in claim 10, at least one moisture barrier sheet disposed within the casing adjacent said carrier member.
12. A safety razor comprising a casing provided with an opening in at least one side thereof, a blade clamp arranged adjacent the opening, a blade carrier member disposed within the casing adjacent the opening, a plurality of blades associated with the carrier member, said member having a plurality of blade receiving faces, and the edges of intersection of said faces being provided with blade guard teeth.
13. In a razor as defined in claim 12, means for positively maintaining the said blades in spaced, parallel relation, and additional means for producing relative movement between the blades and casing.
14. A blade supply magazine for a safety razor comprising a pair of endless belts arranged parallel to each other, and a plurality of spaced blades secured to said belts and all the blades being parallel to each other, and each belt being provided with a plurality of spaced apertures adapted to receive belt driving means.
15. A safety razor including a multi-faced blade carrier member, a blade disposed on each face of said member, said member being provided with a plurality of blade guard edges, a blade clamp arranged in clamping position adjacent at least one of said blades, said carrier member having at least three faces, and said guard edges being provided at the lines of intersection of said faces.
16. In a safety razor as defined in claim 12, at least one moisture barrier sheet disposed within the casing adjacent said carrier member.
17. A blade supply magazine for a safety razor comprising a pair of endless belts arranged parallel to each other, and a plurality of spaced blades secured to said belts and all the blades being parallel to each other, rivet means securing each blade between said belts, and said rivet means extending substantially beyond the belts to permit said rivet means to engage belt driving means.
18. A safety razor including a multi-faced blade carrier member, a blade disposed on each face of said member, said member being provided with a plurality of blade guard edges, a blade clamp arranged in clamping position adjacent at least one of said blades, said carrier member having at least three faces, said guard edges being provided at the lines of intersection of said faces, and means for revolving said carrier member about an axis to replace a used blade by a new blade.
19. A safety razor comprising a rotatable multi-faced blade carrier member having at least two carrier faces, each of the faces being provided with a blade guard edge, said edges being spaced from each other from the width of a carrier face, and a blade disposed on each of the said carrier faces, the blades being positioned to have all cutting edges thereof in the direction of the rotation of the carrier member, the cutting edge of each blade being positioned in contact with its respective guard edge but not extending beyond it.
20. A razor comprising a revolvable multi-faced blade carrier member, said member being provided with a plurality of blade guard edges provided at the lines of intersection of the carrier faces, successive edges being spaced by the width of a carrier face, and means adapted to clamp a blade in cutting position on its carrier face.
21. A razor comprising a revolvable multi-faced blade carrier member, said member being

provided with a plurality of blade guard edges provided at the lines of intersection of the carrier faces, successive edges being spaced by the width of a carrier face, means adapted to clamp 5 a blade in cutting position on its carrier face, and additional means for revolving the carrier member with respect to said clamping means.

22. A safety razor comprising a multi-faced blade carrier member having at least two carrier 10 faces, each of the faces being provided with a blade guard edge, said edges being spaced from each other by the width of a carrier face, a blade disposed on each of said carrier faces, the blades disposed on each of said carrier faces, the blades pointing in same direction along a circular path, 15 the cutting edge of each blade being positioned

in contact with its respective guard edge but not extending beyond it, each of said blades being substantially permanently secured to its respective carrier face whereby after usage the carrier and blades may be discarded as a unit. 5

23. A safety razor comprising a multi-faced blade carrier member, said faces being provided with a guard edge at the line of intersection of successive faces, a blade provided for each of at least two successive faces, means for rotating the 10 carrier member, and the blades being positioned to have all the cutting edges thereof in the direction of rotation of the carrier member. 10
